US00D613328S

(12) **United States Design Patent**
Carlow et al.

(10) **Patent No.:** **US D613,328 S**
(45) **Date of Patent:** **** Apr. 6, 2010**

(54) **3D GLASSES**

(75) Inventors: **Richard A. Carlow**, South Pasadena, CA (US); **Eugenia J. Chen**, Arcadia, CA (US); **Michael J. Chen**, Tustin, CA (US); **Craig Steele**, Hollyglen, CA (US); **Ashley Tilling**, San Juan Capistrano, CA (US); **Roozbeh Mousavi**, Chatsworth, CA (US); **David T. Hamm**, Glendale, CA (US)

(73) Assignee: **X6D Ltd.**, Limassol (CY)

(**) Term: **14 Years**

(21) Appl. No.: **29/314,966**

(22) Filed: **May 13, 2009**

(51) **LOC (9) Cl.** **16-06**

(52) **U.S. Cl.** **D16/300; D16/335; D16/326; D16/325; D16/306**

(58) **Field of Classification Search** D16/101, D16/300–342; D29/109–110; D24/110.2; 351/41, 44, 51–52, 62, 158, 92, 103–123, 351/140, 153, 45–46, 157; 2/426–432, 447–449, 2/441, 434–437, 13, 15; D21/483, 659–661

See application file for complete search history.

(57) **CLAIM**

The ornamental design for 3D glasses, as shown and described.

DESCRIPTION

FIG. 1 is a front elevation view of the 3D glasses;
FIG. 2 is a rear elevation view of the 3D glasses;
FIG. 3 is a side perspective view of the 3D glasses;
FIG. 4 is a top front elevation view of the 3D glasses;
FIG. 5 is a bottom elevation view of the 3D glasses;
FIG. 6 is an isometric perspective view of the front and top of the 3D glasses showing design of our invention; and,
FIG. 7 is a side interior view of the 3D glasses.
